(57) **CLAIM**

The ornamental design for a magic cube puzzle toy as shown and described.

DESCRIPTION

FIG. 1 is a front perspective view of a magic cube puzzle toy showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof;

FIG. 9 is a rear perspective view thereof, showing the magic cube puzzle toy in an open state of use;

FIG. 10 is an enlarged detail view taken from portion 10 of FIG. 1;

FIG. 11 is an enlarged detail view taken from portion 11 of FIG. 8; and,

FIG. 12 is an enlarged detail view taken from portion 12 of FIG. 9.

The broken lines in the drawings depict portions of the magic cube puzzle toy that form no part of the claimed design.

1 Claim, 12 Drawing Sheets
